UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 19,027, dated April 9, 1889.

Application filed March 7, 1889. Serial No. 302,334. Term of patent 3½ years.

To all whom it may concern:

Be it known that I, HENRY HUNT, a citizen of the United States, residing in Greenville, Hudson county, State of New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design is composed of a body, A, and border B. The body A is composed of circular figures of irregular outline and ornamentation, between which are blocks or masses of damask-work of different styles. The border

B is also largely composed of damask-work of different styles, and contains a number of circular ornaments of different patterns and sizes. It is divided by a line of gem-shaped ornaments into two wide bands having ornamental borders. 25

What I claim, and desire to secure by Letters Patent, is—

1. The design for carpets, consisting of the body A, substantially as shown. 30
2. The design for carpets, consisting of the border B, substantially as shown.
3. The design for carpets, consisting of the body A and the border B, substantially as shown.

HENRY HUNT.
